UNITED STATES PATENT OFFICE.

WINFRED E. WILSON, OF SAN PEDRO, AND HOWARD W. WILSON, OF EL SEGUNDO, CALIFORNIA.

APPARATUS FOR TREATING HYDROCARBONS.

Application filed February 1, 1922. Serial No. 533,445.

To all whom it may concern:

Be it known that we, WINFRED E. WILSON and HOWARD W. WILSON, citizens of the United States, residing at San Pedro and El Segundo, respectively, in the county of Los Angeles and State of California, have invented a certain new and useful Apparatus for Treating Hydrocarbons, of which the following is a specification.

Our invention relates to the treatment of hydrocarbon oils to obtain therefrom the various constituent products, and it has especial reference to an apparatus for subjecting oils of the hydrocarbon class to a fractionating process whereby a complete and efficient extraction and recovery of the lighter hydrocarbon products from the crude or other oil treated may be accomplished.

One of the objects of our invention is to provide an apparatus, simple in construction and economical in operation, in which the oil may be subjected to the action of varying degrees of heat, beginning with that low degree required for the liberation of the lighter vapors, and progressing successively with increased temperature till an end point is reached or till all the lighter vapors have been driven off and a residuum is left unaffected by ordinary distilling or fractionating temperatures.

Another object of this invention is to provide a simple apparatus which is automatic in operation and in which the oil may be treated by controllable, non-destructive temperatures; in which the various vaporous products obtained may be separately condensed and collected; in which the heat may be uniformly applied to the oil body or bodies, and in which destructive distillation may be practiced with equal facility as fractionation or distillation.

These and other objects we accomplish by an apparatus illustrated in preferred form in the accompanying drawings, in which,

Fig. 1 is an elevation, partly in section, showing the still, the compartments and baffle plates therein, and the heat conducting tubes.

Fig. 2 is a sectional plan view showing the compartments, the baffles, the heating source and an auxiliary heat conducting means.

Fig. 3 is a vertical section on line 3—3, Fig. 1, showing one of the baffles.

Fig. 4 is a vertical section on line 4—4, Fig. 1, showing another of the baffles.

Fig. 5 is a vertical section on line 5—5, Fig. 1, showing one of the plates or panels in the compartments for maintaining the oil levels therein, and

Fig. 6 is a vertical section showing one of the partitions dividing the compartments.

Our invention comprises in general, a still divided into compartments or chambers, the compartments being intercommunicating and severally provided with means for causing the oil to flow or gravitate in a sinuous path from one compartment to another, and around heat conducting means, through which heat, in the nature of combustion gases, steam, or superheated steam, may be induced to travel. It comprises also a still wherein a continuous treatment or fractionation of the oil may be effected.

Specifically our invention comprises a still chamber 1, inclined to the horizontal to provide a natural gravitational flow for the oil, and divided into a plurality of compartments 5, 6, 7 and 8, by partitions 2, 3 and 4. Each compartment is respectively provided with a plurality of baffle plates 9, 9', 10, 10', 11, 11', and 12, 12', the baffle plates 9, 10, 11 and 12 being connected to one wall of the still chamber and extending to near the other wall thereof to leave a space 13, 14, 15 and 16, and the other baffle plate 9', 10', 11' and 12', being connected to the opposite wall of the still chamber and extending to near the other wall thereof to leave a space 17, 18, 19, and 20. Through these spaces in the respective compartments, the oil, introduced through a pipe 21, is caused to travel, by the tilt of the still chamber in a horizontally sinuous path. In each of the compartments, 5, 6 and 7, respectively, is also a plate 22, 23, and 24, extending entirely across the still chamber and provided at one end with a cut-out portion 22', 23' and 24', seen in Fig. 5, for permitting the oil to flow over said cut-out portions and thence from one compartment to another while maintaining the level of the oil in each compartment. The cut-out portions of the plates 22, 23 and 24 may or may not be of equal heights, but are arranged in such manner that the slope of the still brings each cut-out portion on a plane lower than the preceding one and hence the level of the oil varies progressively in the compartments

and is thus maintained constant during the treatment. To permit the travel of the oil from one compartment to another, the respective partitions 2, 3 and 4, dividing the same, are respectively provided with openings 2', 3' and 4', shown in Fig. 6, on sides opposite to the cut-out portions 22', 23' and 24', of the plates 22, 23 and 24. In this manner and by the withdrawal of the oil 10 from one compartment to another at the bottom of the dividing partition, the oil itself forms a seal for the generated and liberated vapors and prevents the vapors in one compartment from entering another. As 15 seen from Fig. 1, the oil level in each compartment varies, in order to facilitate the gravitational flow from one compartment to another during the fractionating treatment, and the baffles and plates aforementioned, 20 are consequently also of the same height in a single compartment but of different heights in one compartment as compared with the baffle plates of another compartment, and extend sufficiently high above the 25 oil levels to prevent the oil flowing over the top of the same.

In the compartment 8, the level of the oil is regulated by the outlet pipe 25, having a valve 26, and hence the plate 27 therein, is 30 in form and function identical with one of the baffle plates in the compartments. The compartments may be provided with valved drain pipes 28, 29 and 30 respectively, for obvious purposes, the drain pipe for the 35 compartment 8, not being shown. The compartments are also provided on the top thereof with valved vapor lines 31, 32, 33 and 34 respectively, leading to suitable condensers, not shown.

40 The heat for effecting the fractionation of the traveling oil is conducted through a plurality of series of superposed coils 35, 36 and 37, extending through the compartments and the subdivisions thereof formed by the 45 baffles and plates. These coils are connected at the outlet end of the still chamber with a header or distributor 38, through which the heat from a fire box 39 is conducted to and through the coils, the greatest heat being 50 delivered to the compartment 8, to which the oil has traveled through the other compartments and undergone fractionating action, and hence requires a higher heat than that oil in the preceding compartments.

55 Obviously the temperature of the gases traveling or induced through the coils diminishes from compartment to compartment, wherein the oil flows counter to the flow of the hot gases or heating medium, and hence the 60 oil in each compartment may receive just that degree of temperature which is required for fractionation. The series of coils are submerged in the oil, which, as stated, is 65 constantly in flow, and are connected at the inlet end of the still chamber to a header 40,

having communication with a stack 41, by which the hot gases or heating medium is induced from the fire box through the coils. Obviously other means may be provided to induce or force the hot gases or heating 70 medium through the coils.

In order to furnish to the compartments 5, 6 and 7, additional or greater heat, than would ordinarily be conducted through the coils, as where it may be desired to crack 75 or further refine or otherwise subject the oil to dissociating action, the heat from the fire box 39, may be caused to enter directly into the particular coils of one or more compartments, and to accomplish this, we have 80 made the following arrangement. Each of the coils 35, 36 and 37, is provided with a valve 42, for controlling the travel of the hot gases therethrough. Leading from and connected to the header 38, is a plurality 85 of pipes 43, 44 and 45, each connected with the coils extending through each compartment and provided with valves 46, 47 and 48, for controlling the passage of the hot 90 gases from said pipes to the compartments. The pipes 43, 44 and 45, are also provided with valves 49, 50 and 51, near the point 95 of connection thereof with the header 38, in order to prevent the loss of heat when the valves 46, 47 and 48 are closed. When 100 excess or greater heat is required in the compartments or any one of them, the valves 42 may be closed and the valves 49, 50 and 51, opened. Any of the valves 46, 47 and 48, may then be opened as required 105 and the hot gases from the fire box conducted directly to the compartment where the greater heat is desired or required. Obviously the valves 42, may also be left open, 110 in which event the hot gases may travel through the coils 35, 36 and 37, and simultaneously through the pipes 43, 44 and 45, thus providing the greatest amount of heat required in one or more of the compartments.

The oil, as stated, is introduced into the still chamber, through the pipe 21, into the compartment 5 wherein the heat from the coils is sufficient for liberating the lighter hydrocarbon constituents, which collect in the top of the compartment and above the oil, that forms the seal and prevents the passage of the vapors from one compartment to another. The generated vapors are carried from such compartment through the vapor line, as described. From this compartment, the oil travels successively to and through the adjoining compartments, wherein the same steps and actions are performed as in the first compartment, the temperature increasing progressively in each zone.

Where the oil treated has a tendency to foam during the treatment thereof, due to the pressure of water or a condition of emul-

sion, pressure may be maintained on the still chamber by closing the valves on the vapor line, preferably of the compartment 5.

What we claim, is:

- 6 1. An apparatus for treating hydrocarbons comprising a chamber having an inlet and an outlet and divided into a plurality of compartments, the dividing walls of said compartments provided in the bottom thereof with openings, a vapor outlet for each compartment, means in the various compartments for maintaining the oil levels constant, and a plurality of series of superposed pipes within said compartments 10 for heating the oil therein to progressing temperatures.
- 15 2. An apparatus for treating hydrocarbons comprising a chamber inclined to the horizontal and having an inlet and an outlet, said chamber being divided into a plurality of compartments, the dividing walls of said compartments provided with openings in the bottom thereof, vertical baffling means in each compartment, a plate in each 20 of the compartments for maintaining the oil level therein constant, a plurality of series of coils in each compartment and ex-

tending between said baffling means, and means to supply to said coils a heating medium whereby the oil in each compartment 30 is progressively subjected to increasing temperatures in its travel from compartment to compartment.

3. An apparatus for treating hydrocarbons comprising a chamber inclined to the horizontal and provided with a plurality of compartments, the dividing walls of said compartments having openings in the bottom thereof, baffling means in each compartment, a vertical plate in each compartment having a cut-out portion at one side to maintain the level in a certain compartment constant, means to heat the oil in said compartments comprising a series of superposed coils, a source of heat to which said coils are connected, and means connected with the source of heat and with certain of said coils leading in and out of said compartments to supply increased heat to one or more of said compartments. 40 45 50

In testimony whereof we have set our hands.

WINFRED E. WILSON.
HOWARD W. WILSON
